ALPHABET AND NUMERAL REPEAT
PRINTING MECHANISM

Edward J. Rabenda, Ralph E. Page, and Horace S. Beattie, Poughkeepsie, N. Y., assignors to International Business Machines Corporation, New York, N. Y., a corporation of New York

Application October 7, 1948, Serial No. 53,332

5 Claims. (Cl. 101—93)

1

This invention relates to printing mechanisms and more particularly to the type which is adapted to print invariable data generally representing identification or descriptive data which is to be repeatedly printed in accordance with a previous selection.

In certain types of accounting machines, of which the record controlled type is an illustrative type, it is desirable to print at times identification or descriptive data, such as Total, Account No. 1248, Balance Forward, or other such similar words or abbreviations. Such printing can be controlled by the record cards but to avoid the expenditure of columns of the record for this purpose it is desirable to have such printing controlled by an auxiliary device set up in the machine.

The present invention concerns the provision of a device settable in the machine by the operator which provides a control for a printing mechanism to print selected identification data and the provision of selecting means to call such device into operation at desired times.

One feature of the present invention is the provision of a control device which is capable of potentially controlling a printing mechanism to select alphabet and numeral type to print identification data.

Another feature of the invention pertains to the provision of a setup means settable by the operator to select, under control of said device, the desired type of the printing mechanism whereby selected characters, either numerals or alphabet, are printed by the printing mechanism.

A further feature of the invention is to provide a selective arrangement whereby said character selecting device is called into operation for each cycle of machine operation, or for selected cycles of machine operation.

As an explanation of the last named feature, by means of the selective arrangement the same identification data may be printed for each item entering cycle of an accounting machine, or if so desired called into operation for each total taking cycle.

The present character selecting device may be constructed as electrical or mechanical in form, but it is preferable to employ an electrical form of the invention to be able to control an alphabet and numerical printing mechanism of a well known form.

Accordingly, another feature of invention pertains to the provision of an electrical type selecting device comprising an emitter which transmits differentially timed digit representing impulses

2

and zone impulses, useful for digit and alphabet character selection.

Another feature, which pertains to the specific electrical arrangement is to provide an electrical circuit network from said character emitter having wire connections from the digit segments 1—9 of said emitter to digit exit plug hubs or sockets, and wire connections from the O, X, R zone segments of said emitter to alphabet exit plug hubs or sockets which receive not only the digit impulses, but the zone impulses as well. In providing this arrangement it is desirable to direct the zone impulses to the alphabet exit plug hubs by an electrical relay which prevents erroneous impulses from being transmitted by back circuits.

A further feature consists of a circuit arrangement whereby impulses from the digit exit plug hubs and alphabet exit plug hubs are directed to the electrical control instrumentalities of the printing mechanism, directly or selectively by the provision of a selector relay. As illustrative of the use of the latter a selector relay is called into operation whenever a total is taken, and thus only identification data is printed when a total is taken.

Other objects of the invention will be pointed out in the following description and claims and illustrated in the accompanying drawings, which disclose, by way of example, the principle of the invention and the best mode, which has been contemplated, of applying that principle.

In the drawings:

Figs. 1a and 1b when assembled with Fig. 1a on the top shows the construction of the improved numeral and alphabet printing mechanism.

Fig. 2 is a detail of an overthrow preventing mechanism.

Fig. 3 is a view in side elevation showing the intergearing for driving the shafts of the printing mechanism in synchronism.

Fig. 4 is a sectional view taken on the line 4—4 of Fig. 3.

Fig. 5 is a sectional view taken on the line 5—5 of Fig. 3.

Fig. 6 is a sectional view taken on the line 6—6 of Fig. 4.

Fig. 7 represents the preferred code for selecting alphabet and numeral type.

Figs. 8a and 8b when joined together in the order named represent an electrical diagram showing the electrical circuits when the invention is embodied as illustrated in an electrical form.

Fig. 9 is a timing diagram of the machine.

In Fig. 1a reference numeral 38 designates the printing impression drive shaft which is driven with a uniform speed of rotation for each cycle of the operation of the machine. The main drive shaft 22 which rotates one revolution for each item and total taking cycle has secured thereto a gear 40 (Figs. 3 and 4) which drives a gear 41 secured to the printing impression drive shaft 38 to rotate the latter at a uniform speed of rotation one and a half revolutions for each revolution of drive shaft 22. Reference numeral 39 designates the type selecting drive shaft which rotates two and one-twelfth revolutions for each operating cycle. At times shaft 39 is driven with a uniform speed of rotation substantially synchronous with the drive shaft 38, but at other times the speed of rotation given to shaft 39 is decreased or increased with respect to the drive shaft 38 for a purpose to be more clearly understood later on. The variable drive for driving shaft 39 at the desired speed will now be described in detail.

Means to drive shaft 39 at variable speeds (Figs. 3-6)

To the side of the gear 40 and at the periphery thereof, there are secured segmental bearing plates 42, 43. The plate 43 is provided with bearing slots 44 and plate 42 with bearing slots 45. Slidably mounted in such bearing slots is a cam follower plate 46. Hence, plates 42, 43 provide the bearing or support for the slidably mounted cam follower plate 46. Obviously, since the gear 40 carries in this manner the cam follower plate 46, the latter rotates with the gear 40 about the shaft 22 in the same counterclockwise direction (Fig. 3).

Cam follower plate 46 carries a cam follower roller 47, fitting in a cam race 48 of a cam plate 49 which is fixed by studs 50 to a stationary frame plate 51. The cam follower plate 46 has an extension 52 (see Figs. 3 and 6) which carries a stud 53 (Fig. 4) and carried by the stud 53 is a square block 54 fitting between plates 55 secured to one side of a gear 56. So far it is obvious that drive shaft 22 drives the gear 40 and through the connecting cam follower plate 46 the gear 56 is driven. The cam race 48 is so designed that the cam follower plate 46 may be moved away from or towards the center of the shaft 22 and to do this without interference the plate 46 has a longitudinal slot 57 (Fig. 6) encircling the shaft 22. Also in view of the movement given to gear 56 at times resulting from the movement given to cam follower plate 46 by the cam race 48 and which movement is relative to the gear 40, the gear 40 has an elongated slot 58 (Fig. 6) through which the stud 53 passes.

The gear 56 (Figs. 3 and 5), through the gear 59, drives the type selecting drive shaft 39 and thus the latter through the variable gear drive just described is driven at a variable speed through the operating cycle of the printing mechanism. For the proper operation of the machine disclosed herein main drive shaft 22 is driven counterclockwise as viewed in Fig. 3.

A group of type consisting of three alphabet type and one numeral type is allocated for each impulse 1-9, as shown in the code of Fig. 7. Shaft 39 is driven at a uniform speed of rotation between 120° and 270° and for each 15° four printing type (4T) past the printing line (see Fig. 9). At about 270° the speed of rotation of the shaft 39 starts to decrease so as to present four print-

ing type past the printing line for 27°. Between 120° and 270° of the cycle of operation the roller 53 will cooperate with a substantially concentric portion of the cam race 48, and since there will be no movement of cam follower plate 46 during this period gear 56 will be driven counterclockwise at the same speed of rotation as the gear 40. When the cam follower roller 47 enters an eccentric cam portion between 270°-300° the speed of rotation of the shaft 39 is reduced so that four printing type are presented for 27°. Between 300°-345° the eccentric part of cam race 48 so reduces the speed of shaft 39 that for each 15° only one printing tooth (1T) will pass by the printing point. At 300° the alphabet type which would be selected by the O impulse will be adjacent the printing line. At 315° of the cycle of operation the alphabet type of the selected group selected by the X impulse will be in position for printing at 330° the alphabet type selected by the R impulse will be in a position to print and at 345° the numeral type of the selected group will be in position to effect an imprint therefrom. Therefore, the slowing down of the speed of the rotation of shaft 39 is provided to selectively effect printing from the selected alphabet or numeral type of the selected group.

During the time that the cam follower roller 47 enters the very eccentric cam portion of cam race 48 between 300°-345°, the cam follower plate 46 under control of the cam race 48 moves outwardly (Fig. 3) with respect to the center of the shaft 37, thus, rotating the gear 56 in a clockwise direction opposite to the counterclockwise direction of rotation of the gear 40. This will result in diminishing the speed of rotation of the gear 56 and shaft 39 during the transmission of the O, X and R zone impulses as just described.

After this reduction in speed of gear 56 the follower roller 47 then enters the cam portion after 345° and the latter is so designed as to move plate 46 inwardly (Fig. 3) towards the center of shaft 22 to cause gear 56 to rotate counterclockwise at a speed increased with respect to the gear 40. This increase in speed is initiated at 345° of the operating cycle and continues on over to the next operating cycle to 120° thereof. This increase in speed during such portions of successive machine cycles ensues to make up for the previous relative displacement of gear 56 so that at 120° of the cycle the gears 40 and 56 and parts driven thereby are always at the same relative position.

Alphabet printing mechanism

The machine is preferably provided with alphabet type and impulse means for selecting such type so as to print, aside from numerals, letters making up words or abbreviations.

The printing mechanism shown herein is also shown and described in the patent to R. E. Page and H. S. Beattie, No. 2,438,071, dated March 16, 1948.

The alphabet type are selected by impulses according to the code shown in Fig. 7. The particular O, X and R impulse determines which of the several type of a group selected by an impulse 1-9 will be printed. For example, if the impulse is "2" and no pilot impulse is utilized, either the O, X or R impulse, the digit 2 will be printed. If an impulse is also at O such impulse will select the type S; if the X impulse type K will be selected and if the R impulse type B will be selected.

Each impulse 1-9 selects a group of three non-numeral type and also a numeral type. As will be later described, if a numeral type is to be selected for printing, the printing impression will be taken at the "N" point in the machine cycle, which point is after the R zone impulse (see Fig. 9, timing for "N impulse"). The alphabet type selection is provided for by taking printing impressions before the time a numeral type would have been printed and this is effected under control of the O, X and R impulses.

If the impulse is 9 alone, a printing wheel 60 (Fig. 1a) will be rotated counterclockwise until the 9 type is at the printing line and then the printing wheel 60 will be rocked by the N pulse to effect the printing impression. It will be noted that if the impulse is R then under control of this impulse the printing wheel will be rocked earlier than for printing the digit 9 to take an imprint from the I type. The X impulse will rock the printing wheel 60 to take an imprint still earlier to print R and the impulse O even still earlier to print Z.

The same principle of operation is provided for selecting the type of the other groups of alphabet type and the operation of the printing mechanism for effecting type selection and printing impressions will now be described in detail.

The impulses are transmitted in the order 9, 8, 7, . . . 1, O, X and R.

When the 9-1 impulses are transmitted a circuit is closed to a printing control magnet 61 (Fig. 1b) and for each column there is a printing control magnet. In the present machine by mechanisms to be subsequently described in detail, this initiation is effected by the actuation of an operating link 63 (Fig. 1a) at a differential time. For selection of type groups determined by the impulses 9-1, such operating link 63 is shifted to the left at differential times between 135-270° of the operating cycle as is shown in the timing diagram (Fig. 9). It will also be recalled that during this time shaft 39 is being rotated at a uniform speed of rotation. The shifting of the operating link 63 at differential times is provided herein to transmit a differentially timed mechanical impulse to trip the type selecting clutch shown in Fig. 1a, now to be described in detail.

For each printing order there is pivoted on a rod 66 a triple arm member consisting of arms 64, 65 and a clutch release arm 67.

Shaft 39 has secured thereto a tube 68 which is fluted transversely along its periphery to provide clutch notches 69. Tube 68 constitutes the driving clutch member. Encircling the clutch tube 68 is a plurality of gears 70, there being one gear for each order of the printing mechanism. For mounting the gears 70 on the clutch tube 68, each gear has integral therewith a flange 72. To provide for the lateral spacing between the gears 70, the gears are guided by guide slots 71 formed in guide blocks 73, 74 and 75. By such spacing members the gears 70 are separated to allow independent rotation and to also locate a clutch pawl 76 which is pivoted on the related gear to cooperate with the clutch release arm 67. The clutch release arm 67 normally holds the clutch pawl 76 in such position that its tooth 77 is out of engagement with any of the clutch notches 69 of the clutch tube 68. When the clutch release arm 67 is rocked as a result of the actuation of the operating link 63 at a differential time the clutch is engaged because a spring 78 attached to clutch pawl 76 will rock the latter in order that the clutch tooth 77 will engage a clutch

notch 69 determined by the differential time the operating link 63 is actuated. The above described clutch is the printing type selecting clutch and causes the differential rotation of the printing wheel 60, since the gear 70 and the printing teeth of the type carrying wheel 60 are intergeared.

Figs. 1a and 1b show the arrangement of the printing devices for a single order and the machine is preferably provided with duplicate devices for printing a plurality of characters.

If the operating link 63 was shifted at about 138° as a result of the 9 impulse, the clutch release arm 67 would be rocked at this time and pawl 76 would be released and rocked by spring 78 so that clutch tooth 77 engages a clutch notch 69 and printing wheel 60 will thereafter continue to rotate to such position as to successively present the characters Z, R, 1 and 9 of the group selected by the 9 impulse (see Fig. 7) to the printing line between 333°-345°. The differential time at which the operating link 63 is actuated determines the extent of counterclockwise rotation of the printing wheel 60 necessary to select a group of type for printing between 330°-345°. After the predetermined extent of rotation of the printing wheel 60 has been effected and the printing impression has been effected, with the type selecting clutch still engaged, the printing wheel 60 will continue to rotate until the free end of the clutch pawl 76 strikes the clutch release arm 67 which, in the meantime, has been brought to its normal position, by means of a compression spring 79 (Fig. 1a). When such disengagement is effected the printing wheel 60 is at the normal position shown in Fig. 1a.

Each printing wheel 60 is carried by an arm 81 loosely pivoted upon a rod 82 and provided with a rearwardly extending follower extension 84 which is operated by a cam projection 83 of a cam disk 85 which constitutes a driven member of a printing clutch.

Shaft 38 rotates a clutch tube 86 fixed thereto and likewise encircling the clutch tube 86 is the driven clutch disk 85 upon which is pivotally mounted a clutch pawl 87. Clutch disk 85 and parts carried thereby are guided similarly to gear 70. Associated with the clutch pawl 87 is a clutch release arm 88. When the clutch engagement is effected between the clutch pawl 87 and one of the clutch notches of the clutch tube 86, the disk 85 will be rotated in a clockwise direction, whereby the cam projection 83 will cooperate with the follower extension 84 to rock arm 81 about the rod 82 against the action of the return spring 89. The engagement of the clutch now being described is effected at differential times when the printing control magnet 61 for each order is again energized under control of the O, X and R impulses.

At the present time it should be understood that while the O, X and R impulses are being transmitted the clutch release arm 88 will be rocked to clutch release position. As a result of this clutch engagement, the cam extension 83 approaches the follower extension 84 at the time shaft 39 is rotating at a diminished speed between 330°-345°, to present the type of selected group successively to the printing line. Thus, the particular type which is to be selected from the selected group for printing will depend upon the differential time that the printing control magnet 61 receives a second impulse and, therefore, the time at which the printing clutch is engaged. If the O impulse is transmitted the

printing clutch is engaged at the earliest time so as to select the first alphabet type of the selected group. If the impulse is X the printing clutch is engaged at a later time when the next alphabet type of the selected group is at the printing position and obviously when the impulse is R the printing clutch will be engaged at a still later time when the third successive alphabet type of the selected group is at the printing position. By the engagement of the printing clutch at a differential time the desired alphabet type and the numeral type of the selected group may be selected.

When the printing clutch engagement has been effected each cam 85 will cooperate with the related follower extension 84 to rock the associated printing arm 81 to force the printing wheel 60 against the usual inking ribbon and platen 90 around which platen is positioned the paper strip to be imprinted. As each arm 81 is rocked against the action of the spring 89, the printing wheel 60 is being rotated counterclockwise but since the printing wheel is now rolling over the gear 70 this rolling action will cause an equal and simultaneous rotation in a clockwise direction. Both of these opposite rotations will, in effect, cause the printing wheel to be immobile with respect to its rotation when it moves to the right to strike the platen 90, the type striking the platen squarely and firmly to cause a legible impression.

After the printing operation, when cam extension 83 of the cam disk 85 passes by the follower extension 84, spring 89 will now be effective to return the type wheel carrying arm 81 to normal position and the extension 84 now bears against the circular peripheral edge of the cam disk 85.

After the printing operation, since the type selecting clutch is still engaged, the printing wheel 60 continues to rotate as previously stated until the clutch pawl 76 strikes the clutch release arm 67 which, in the meantime, has been positioned to normal, thereby disengaging the type selecting clutch when the printing wheels are at normal position.

The printing clutch continues its engagement for a complete rotation of the cam 85 and the clutch disengagement is effected by the engagement of the clutch pawl 87 with the clutch release arm 88.

It has been found in practice that when the disengagement of the pawl 76 for the type selecting clutch is effected by striking the clutch release arm 67, there is a tendency of the clutch pawl 76 to rock counterclockwise about its pivotal point, unduly stretching the spring 78. To prevent this action a cushioning arrangement is provided to hold the pawl 76 and is shown partly in the lower right-hand corner of Fig. 1a and more completely in Fig. 2. In a preferred arrangement this constitutes for each type selecting clutch a double arm 92. One arm cooperates with a cam portion 93 of the clutch pawl 76 and the other arm bears against a spring pressed plunger 94 inserted in an aperture 95 partially filled with oil. As the clutch pawl 76 comes around to its normal position, it will strike the clutch release arm 67, forcing its clutch tooth 77 out of the clutch notch 69 it previously engaged and the cam portion 93 of the clutch pawl 76 will strike one arm of the double arm 92, forcing the opposite end downwardly to press the plunger 94. This will force the oil out of the bottom of the recess 95 and around the plunger 94, thus providing a cushioning action on the arm 92 to

75 restrain the clutch pawl 76 so that it cannot move too far outward.

As the free end of the clutch pawl 76 strikes the clutch arm 67 there is a tendency to cause the gear 70 to rebound counterclockwise. This action is prevented by the cooperation of a spring-pressed detent 96 with a shoulder 97 of a plate 98 secured to each gear 70. When the normal position of the clutch is obtained, the detent 96 will engage the shoulder 97 to prevent such rebound and retain the clutch parts in their normal position.

A somewhat similar rebound preventing mechanism is also provided for the printing clutch which consists of a spring pressed detent 91 cooperating with the shoulder 99 of the cam disk 85.

Translating and impulse converting arrangement.

The purpose of the above arrangement herein is to translate and convert differentially timed electrical impulses to mechanical impulses and delay the transmission of each mechanical impulse to a later point in the cycle for the purpose of selecting a group of type corresponding to the differentially timed electrical impulse transmitted.

Herein the converted and delayed mechanical impulse is used for the purpose of type group selection. The arrangement for one denominational order is shown in Figs. 1a, 1b and 2.

Cams 100A, 100B, 100C and 100D are driven by driving means to be subsequently described one revolution for each cycle of operation of the machine. It will be noted that these cams differ in their cam contours and the particular cam portion which is effective in each point of the operating cycle is shown in the timing diagram of Fig. 9. Each of the cams is provided with cam heights which are identified by three dotted circles associated with the cam 100A (Fig. 1b), which circles are of three different diameters and represent the heights of the cam contours as "low," "medium" and "high." The corresponding designation is shown in the timing diagram of Fig. 9 for such cams to identify the particular cam portion effective in each point of the operating cycle. The cams 100A, 100B, 100C and 100D may for convenience in construction be extended longitudinally as shown in Figs. 4 and 5 to provide fluted-cam rods having the configuration and outline in Fig. 1b to cooperate with a plurality of orders.

Each cam 100 cooperates with a related releasing and blocking member 110. The reason that the member 110 is called releasing member is that when elevated a predetermined distance by the "medium" or "high" cam portion of the related cam 100 it will release the operating link 63 for movement but when in its normal lower position (due to the "low" cam portion) it will block the link 63 against movement. Each member 110 is slidably mounted in a slot 101 of a guide block 102 and is further guided by a rod 104 which receives a guide slot 103 of the related member 110. Also pivoted on a rod 105 carried by the block 102 is a latch pawl 106. Interposed between the pawl 106 and the associated member 110 is a compression spring 107, the spring 107 functioning to urge the member 110 downwardly so as to always press against and contact with the cam contour of the related cam 100. Each member 110 is provided with a shoulder 108 cooperating with a lug 109 formed as an integral part of the link 63.

The link 63, referring to Fig. 1a, is slidably mounted in guide slots formed in a support plate 111 to support the link 63 at one end and guide its movement, and referring to Fig. 1b the other end of the link 63 is dependently hung by arm 113, which arm has a cam follower extension 118. A compression spring 114 fitting in a spring support and guide block for arm 113 urges the link 63 to the left and when such spring is effective for action under control of a cam 125 it serves as the source of mechanical impulse transmitted to link 63 at a differential time to rock the clutch release arm 67 to initiate type group selection. Recalling now that each cam 100 has cam contours of three different heights, it should be observed that when member 110 is at a position determined by the low portion of the cam 100, the shoulder 108 abuts lug 109 to block the link 63 from movement to the left, urged by compression of the spring 114. In attempting to do so lug 109 will bear against the shoulder 108 and urge the member 110 clockwise, which movement is restrained by the cooperation of an upstanding hooked portion 112 of member 110 against the latching end of the pawl 106. Assuming now that a cam has been rotated so that the "medium" cam portion of the cam contour has raised the member 110, such difference in cam height with respect to the "low" cam height will elevate shoulder 108 slightly further above the related lug 109, and by the continued cooperation of the hooked extension 112 of the member 110 with the extremity of the pawl 106, clockwise movement of the pawl 110 will be still restrained.

Assuming now that the "high" cam portion has positioned the member 110 to its maximum height, the shoulder 108 will be still further above the lug 109 and the member 110 is now in such position that the compression spring 107 will be effective to rock the member 110 clockwise so that a hooked extension 112 will catch over the latch end of pawl 106, provided that at this time the pawl 106 is rocked counterclockwise due to the concurrent transmission of an impulse at the time the member 110 is in its highest position. If the pawl 106 is not rocked slightly counterclockwise, no latching of the member 110 will take place. Summarizing, whenever the "high" portion of a cam has elevated a member 110 to the highest position, such member will be latched if the related pawl 106 is concurrently rocked to latching position. If there is no rocking of the pawl 106 at this time, member 110 will not be latched, and will be subsequently free to move up and down in accordance with the successive cam contour as the related cam 100 rotates.

The above description has been confined to the operation of the parts under control of the cam 100A but it should be noted that identical operations are effected under control of the remaining cams 100B, 100C and 100D. For this reason, the description of operation need not be repeated for duplicate parts.

For the purpose of rocking the pawls 106 to latch those members 110 which are at their highest position at the time an impulse is transmitted, it will be seen that referring to Fig. 1b each magnet 61 when energized attracts an armature 115 and rocks the same so as to shift a related connected link 116 to the left. Depending from the link 116 are four integral extensions 117, each of which cooperates with the related pawl 106. The result of this construction is that the impulse directed to the magnet 61 will shift the link 116 and rock the four pawls 106 concurrently but only

that pawl 106 is effective for latching the related member 110 if the associated member 110 has been elevated to its highest position. Therefore, one or more of the pawls 106 may be rocked idly at the same time without latching the related members 110.

To prevent the armature 115 from sticking to the core of the magnet 61 due to residual magnetism, it is desirable to provide means to positively restore the link 116 and armature 115 to normal by mechanical means timed with the rotation of the cams 100. To this end there is provided at magnet knockoff cam 120 (Fig. 1a) notched as shown. A follower arm 121 of a clutch release arm 124 cooperating with the cam 120 has a mechanical connection 122 with the link 116. At the time the magnet 61 is energized it will be observed that follower arm 121 cooperates with a notch 120a of the cam 120. Thereafter, such arm cooperates with the following cam portion 120b to rock arm 121, link 116 and armature 115, restoring the armature 115 to normal if it should remain attracted to the core under the above circumstances.

Referring now to Fig. 9, it is obvious that at the time the impulses 9-1 are transmitted, one or more cams 100 will have their "high" portions in cooperation with the latching members 110. At the time the 9 impulse is transmitted the high portions of cams 100A and 100C will be effective. At the time the 8 impulse is transmitted only cam 100A will have a high portion effective at this time. For all of the impulses 9-1, this condition may be represented by the following table:

	Impulses	Members 110 Latched
9		110A, 110C
8		110A
7		110B, 110C, 110D
6		110B, 110C
5		110B, 110D
4		110D, 110C
3		110B
2		110C
1		110D

It is obvious from the above table that members 110 are latched singly or in predetermined combinations, so that at the termination of the transmission of the impulses 9-1, some of the members 110 will be latched and others will not be latched and therefore free to be positioned according to the contour of their cams during their subsequent rotation. It is explained that once a member 110 is latched it is not free to thereafter move upwardly and downwardly in accordance with the subsequent cam contour of the related cam, but remaining unlatched members can do so.

Cam 125 through driving means to be subsequently explained, is driven synchronously with the cams 100 and 120 and cooperates with the follower extension 118 of arm 113.

After latching of members 110 in predetermined combinations the contour of the cams 100A, 100B, 100C and 100D which are thereafter effective will determine the time in the operating cycle that the operating link 63 will be moved to the left in a manner now to be described in detail:

After one or more members 110 are latched in combination according to the impulses transmitted as indicated in the preceding table, the further rotations of the cams 100 will raise and lower the remaining unlatched members 110 according to the cam contours of the respective

cams, but during said further rotation of the cams the link 63 will be restrained against movement by one or more of such unlatched members until a point is reached in the operating cycle when the cams related to the unlatched members concurrently present cam operations of "medium" height to the unlatched members. It will be recalled that since the latched members 110 are so positioned that they do not restrain the movement of the link 63 under the influence of the spring 114 and further the elevation of any unlatched member by a cam portion of "medium" height will also unlock the link 63, it is obvious that when both of these conditions exist for four of the latches 110, the link 63 is then free to move under the influence of the spring 114 and cam 125. This will be made clear by reference to a particular example.

If, for example, the 9 impulse is selected, members 110A and 110C are latched due to the "high" cam portion of their respective cams 100A and 100C and such latching of members 110A and 110C occurs about $7\frac{1}{2}$ ° of the operating cycle when the 9 impulse is transmitted (see Fig. 9). At this time the members 110A and 110C are latched in the highest position so that they unlock the operating link 63 at such positions. However, cams 100B and 100D in their subsequent rotation continue to raise and lower the related unlatched members 110B and 110D and one or the other of such unlatched members 110B, 110D will restrain the operating link 63 from movement until about 138° of the operating cycle, at which time both cams 100B and 100D, through their "medium" high cam portions, shift related latching members 110B and 110D to unlock the link 63. At this time cam follower extension 118 of the arm 113 will cooperate with the notch 125b designated "9" in both Fig. 1b and the timing diagram of Fig. 9. Operating link 63 is now unlocked at four points and the movement of the link to the left is effected at about 138° by spring 114. The link will now operate the clutch release arm 67 and therefore engage the type selecting clutch to initiate the rotation of the printing wheel 60 to select the group of type, 9, Z, R and I.

The type selecting clutch will be engaged at about 150° of the operating cycle and from the timing diagram (Fig. 9) the type carrying wheel 60 will rotate 4, 4, 4, 4, 4, 4, 4, 4, or thirty-six teeth, and at about 300° of the operating cycle the Z type will now be in position to print. At 300° of the operating cycle, the speed of rotation of the type wheel is decreased to successively present the type of selected group in the order Z, R, I, and such type are selected for printing in accordance whether the pilot impulse is O, X or R.

Reverting now to Fig. 1b, when the operating link 63 is moved to the left to effect the engagement of the type selecting clutch the cam follower extension 118 is in the bottom of the notch 125b of the cam disk 125 and further rotation of the cam 125 in a clockwise direction will, through the following inclined cam portion 125c, cooperate with the cam follower extension 118 to positively restore the operating link 63 to the right without, however, causing the unlatching of any latched member 110. At about 330° an extra high cam portion 125d will shift link 63 to the right beyond the Fig. 1b position, and in so doing for those members 110 which have been unlatched lug 109 will engage the shoulder 123 of the respective member 110 to rock the same

counterclockwise to unlatching position, spring 107 being compressed during this operation to rock the pawl 106 to normal position shown in Fig. 1b. With respect to any unlatched member 110, movement of the operating link 63 to the right at this time may also effect movement of such members 110 but the operation of such is ineffective.

It is desirable to provide means to insure that the clutch release arms 67 are at their normal position and will remain so when engaged by the extremity of the clutch pawls 76 to unlatch the latter from the ratchet teeth 69. Such means now to be described is independent of the springs 15 79. Referring to Fig. 1b there is pivoted on a shaft 128 a plate which has fixed thereto a comb plate consisting of spring formed fingers 129 which bear against the lower extensions 65 of the clutch release arms 67. Attached to shaft 128 is 20 a follower arm 130 carrying a roller 131, cooperating with a cam 132 secured to a drive shaft 143. From Fig. 9 it will be seen that a cam rise 132a operative at about 306° of the operating cycle is effective to cooperate with the follower 25 roller 131 to rock the shaft 128 counterclockwise, pressing the spring fingers 129 against the related extensions 65 of the clutch release arms 67, positively retracting them to the normal position shown in Fig. 1a. Thus, it is insured that 30 clutch release arms 67 will be in such position that they will be in the path of the free ends of the clutch pawls 76 to move them to unclutching positions.

A low portion 132b of such cam 132 is effective 35 to enable the follower arm 130 to be rocked by a spring 133 to cooperate with such low portion 132b which releases the spring pressure on the clutch release arm 67 to free the latter for rocking to engage the type selecting clutch.

Upon transmission of such O, X, R impulses 40 through circuits to be described, the second energization of the magnet 61 again attracts its armature 115 and shifts link 116. The latter thereupon rocks the clutch release arm 125 to 45 unlatch the clutch release arm 88 of the printer thereupon rocks the clutch release arm 124 to Figs. 1a and 9) of cam 120 cooperates with the cam follower extension 121 so as not to restrain the rocking of clutch release arm 124. When 50 the clutch release arm 88 is unlatched a depending extension 127 moves in a clearance portion 126 of said arm 124. Cam disk 83 will now rotate clockwise and the cam extension 83 will strike the follower extension 84 at the time the selected 55 type is at the printing line to effect the printing impression.

It is undesirable to have the clutch release arm 88 released whenever link 116 is rocked the first time to rock arm 124 and to this end a high portion 137a of cam 137 cooperates with arm 88 to block it against movement to release the printing clutch during transmission of impulses 1-9. When impulses O, X and R are transmitted the low portion of cam 137b (see Fig. 9) will 60 cooperate with clutch release arm 88 to permit its rocking to engage the printing clutch. After the transmission of the O, X, R impulses the cam rise 137c of cam 137 will function to positively retract the clutch release arm 88 to normal position to cause disengagement of the clutch release pawl 87 after a complete revolution of the printing clutch. At the termination of the operating cycle, a cam rise 120d of cam 120 functions to rock the clutch release arm 124 clockwise to again position it beneath the extension 65 70 75

135 of the clutch release arm 88, which previously has been elevated to the position shown in Fig. 1a. The cam rise 120d also shifts link 116 to restore armature 115 to normal if it should stick to the core of magnet 61.

While the operation of the machine has been described in connection with the selection of the group of type under control of the 9 impulse the same principle of operation for effecting the above results is involved for other impulses as is evident from the following table:

Impulses	Members 110 Latched	Mechanical Impulse at—	Cams 100 at Medium Cam Portion
9	110A, 110C	138	100B, 100D
8	110A	153	100B, 100C, 100D
7	110B, 110C, 100D	168	100A
6	110B, 110C	183	100A, 100D
5	110B, 110D	198	100A, 100C
4	110C, 110D	213	100B, 100A
3	110B	228	100A, 100C, 100D
2	110C	243	100A, 100B, 100D
1	110D	258	100A, 100B, 100C

It will be recognized from this table that the concurrent position of cams 100 at a "medium" height cam portion for those cams which have not previously latched members 110 will determine the time the mechanical impulse is transmitted.

The machine includes a driving means driven by the shaft 22 for rotating the cams 100A, 100B, 100C and 100D, 120, 125, 132, and 137 in synchronous relationship and such cams are driven one complete revolution for each operating cycle.

The driving means for driving cams 100A, 100B, 100C and 100D will now be described. Secured to shaft 22 is a gear 140 (Fig. 3) which, through a gear 141, drives a gear 142 secured to the drive shaft 143 for the cam 100D and cam 132. Shaft 22 is extended, as shown in Fig. 5, to directly drive the cam 100C. Referring to Fig. 3, gear 140, through a gear 144, drives a gear 145 secured to the drive shaft 146 for cam 100B. Gear 145 through an idler gear 147 drives a gear 148 secured to the drive shaft 149 for the cam 100A. By such driving means the cams 100A, 100B, 100C, 100D and 132 are driven synchronously.

Referring to Fig. 3 gear 144 has rotatable therewith a gear 150 which, through an idler gear 151, drives a gear 152 attached to the shaft 153 to which the cam 125 is secured.

Gear 150 also meshes with a gear 154 secured to a shaft 155 to which shaft the cam 120 is secured.

Also referring to Fig. 3 to drive shaft 38 there is secured a gear 156 which meshes with a larger gear 157 secured to a shaft 158 to which shaft the cam 137 is secured.

Thus, through the intergearing last described, the operating cams 120, 125 and 137 are driven synchronously with the operating cams 100A, 100B, 100C and 100D.

Wiring diagram

The operation of the machine will now be explained in connection with the wiring diagram of Figs. 8a and 8b and an exemplary setup will be described to show the manner of printing, by the printing mechanism previously described, numeral and alphabet characters.

Power is supplied by line wires 160 and 161. EM refers to an emitter of a well known type which is adapted, during each cycle of operation of the machine, to emit impulses representative

of the digits 1-9 and the zone impulses O, X, R, said impulses having the timing shown in Fig. 9.

In details of construction of emitter EM there is secured to the main drive shaft 22 a double brush of which brush 163 makes contact with the digit segments 9-1, O, X, R in succession during the time the other brush 164 makes contact with an arcuate segment 165 which has a connection 166 to the line side 160. Shaft 22 is a continually rotating shaft which rotates in both item entering and total taking cycles in order that selected character printing may be effected in either item or total printing operations, or both, as is desirable. From the segments 9-1 there are nine wire connections 167 which terminate at a corresponding number of exit plug hubs or sockets 168 which are shown as single hubs but may be dual or triple plug hubs for multiple plugging operations. Hence, it is evident that the emitter EM transmits digit representing impulses to the plug hubs 168 and in accordance with the plug connections made from the digit plug hubs 168 to the print control magnets 61 several orders of the latter may be energized at differential times to select corresponding numeral type.

A series of plug hubs 169 are provided for the print control magnets 61 so that desired columns on the sheet may be imprinted. From each plug hub 169 the circuit extends through the respective normally closed transfer contacts 1-10 of the R12 relay, the associated control magnet 61, to the line side 161.

If so desired plug connections may be made directly between the plug hubs 168 and 169 so that selected character printing can be carried out for each item or total printing cycle of operation of the emitter EM but it is preferable to cause such character printing at selected operations of the machine which, in the instant case, is selected by the R5 relay. Said relay when energized is adapted to close a group of relay contacts 1-12, thereby connecting each plug socket 170 with a related plug socket 171. When relay R5 is used to call character printing operations at selected times, plug connections are made from plug hubs 168 to plug hubs 170 and plug connections are made from plug hubs 171 to plug hubs 169. Four of the plug connections 172 are shown between plug hubs 168 and 170 and four 50 173 between plug hubs 171 and 169 for effecting printing of the characters 4, 3, 2, 1 on the sheet. It is evident that with such plugging the EM emitter will transmit differentially timed impulses 4, 3, 2, 1 to the control magnets 61 of four columns and the printing mechanism will operate to print the digits -4321- upon the sheet. Of course, by means of suitable plug connections from any of the plug hubs 168 the digits to be printed can be varied and when so connected, repeated printing of the digits will be effected for each operation of the machine, or an operation which is selected by the R5 relay. The manner in which the R5 relay is energized to selectively call the printing operations will be explained later.

The energizing circuit for energizing each print control magnet 61, taking for example, the selection of the digit 4 for printing, is from the line side 160, wire 166, segment 165, brush 164, brush 163, the 4 digit segment, related wire 167, the plug hub 168 designated "4," plug connection 172, plug hub 170, the R5-9 relay contacts now closed, plug hub 171, plug connection 173, plug hub 169, R12-6 relay contacts now normal, print control magnet 61, to the line side 161.

75 It was explained that printing of the selected

numeral character is effected by transmitting a second impulse to the print control magnet 61 at the "N" impulse time, or about 185° of the machine cycle. To transmit the second "N" print effecting impulse to the control magnet 61, the following circuit is provided: Before the N impulse time, at about 180°, CR6 cam contacts close so as to pick up, by an obvious circuit, the R12 relay which transfers its 1-10 relay contacts and holds such contacts transferred at the time the CR2 cam contacts close at the "N" impulse time. The impulse circuit for transmission of the N impulse is from the line side 160, through CR2 cam contacts, wire 174, thence through the respective 1-10 relay contacts of R12 relay, the 15 print control magnet 61 to the line side 161. This impulse causes printing from the selected numeral digit.

For alphabet character printing it will be recalled that impulses are transmitted in combination, that is, in addition to one of the digit impulses 1-9 the selected zone impulse O, X, R is also transmitted to the control magnet 61. To this end from the digit segments O, X, R of EM emitter there are three wire connections 175 which are connected to the respective R line 176, the respective X line 177 and the respective O line 178. For selecting the desired alphabet characters for printing there are three rows of nine plug hubs or sockets. Row 180 comprises nine plug hubs for letters of the alphabet A-I, row 181 of nine plug hubs for printing letters J-R, and the third row of nine plug hubs 182 for printing the remaining letters of the alphabet S-Z, and if so desired, the symbol /. The row of plug hubs 180 receives the digit impulses 9-1 through the normally closed side of the transfer contacts 1-9 of the R1 relay; the row of plug hubs 181 receive digit impulses 9-1 through the respective 1-9 contacts of the R2 relay, and in a similar manner for the row of plug hubs 182 through closed contacts 1-9 of the R3 relay, all connected according to the code of Fig. 7. The second or zone impulse is transmitted in the following manner: Referring to Fig. 9 cam contacts CR1 close during the time of the transmission of the O, X, R zone impulses by emitter EM, thereby energizing the R1, R2, R3 relays by an obvious circuit shown in Fig. 8b. R3 relay transfers its 1-9 contacts, thus causing the zone impulse O to be transmitted to the series of plug hubs 182. R2 relay transfers its 1-9 contacts to cause the X zone impulse to be transferred to the series of plug hubs 181 and R1 relay causes the R impulse to be transmitted to the plug hubs 180. Thus, the desired combinations of impulses are transmitted to the alphabet plug hubs 180, 181 and 182.

Five plug connections 183, 184, 185, 186 and 187 are shown, by way of example, from the four alphabet plug hubs designated Total to plug hubs 170 so that upon energization of the R5 relay when taking a total, the circuit will be extended through the respective relay contacts, plug connections 188, to plug hubs 169, the normally closed transfer contacts of the R4 relay, to the print control magnets 61. Thus, the selected O, X, R impulse will be transmitted to the print control magnets 61 to select the desired alphabet character of the group selected by the previous digit impulse 9-1. Of course, the plug connections shown are merely exemplary and by plug connections from the series of plug hubs 180, 181 and 182 alphabet printing may be effected to print other words, abbreviations, etc. Not only may desired digit and alphabet printing be carried out

singly or in combination but by placing symbol type on the print wheel such symbols may also be printed.

If so desired the machine may be arranged so that by employment of the printing mechanism shown in the patent to R. E. Page, No. 2,438,071, dated March 16, 1948, combinations of digit impulses may be used to print the symbols printed by the printing mechanism of this patent. This will additionally extend the usefulness of the present invention when it is so modified to secure this result.

It is desirable to call the character selecting emitter into operation only during selected machine cycles and to illustrate the manner of carrying out this feature of the invention there will be described the means for calling this device into operation during a total taking operation. When the present invention is embodied in record controlled accounting machines such total taking operations are automatically initiated by the group control means which will now be described. In other types of machines the calling in of the printing control device into operation may be effected by other means.

Referring now to Figs. 8a and 8b it will be recalled that the character selecting emitter EM is called into operation as a result of the energization of the R5 relay and herein is energized under control of the group control means. The change in the group number is detected by the comparison of perforations analyzed at the UB or upper reading station with perforations on another card analyzed at the same time by the LB or lower brush reading station. In each station reference numeral 192 represents the contact roll and 193 the analyzing brushes. Current to the brushes at each analyzing station is provided by the CR3 circuit breaker contacts which connect line side 160 with each contact roll 192. From the brushes 193 at the upper reading station there are three plug connections 194 which terminate at plug hubs 195 which are connected to the respective pickup coil of the R6, R7 and R8 relays which are connected by wire 196 to the line side 161. Similar plug connections 197 are made for the lower reading station so as to energize the pickup coils of the R9, R10 and R11 relays. A hold circuit is effected for each of the relays R6 to R11, through the respective h contacts, back through the CR3 circuit breaker contacts to the line side 160.

It is evident that upon a concurrent analysis of the corresponding holes in the corresponding column of the two cards the R6 and R9 relays will be concurrently energized, the R7 and R10 relays and the R8 and R11 relays. Upon dissimilarity in perforations in the same column one of the pair of relays, such as R6 and R9, will be energized at different times.

The comparing circuit is identical for the three orders of the group control shown herein and consists of a circuit network of the "b" transfer contacts. For example, the R6 and R9 relays have their "b" transfer contacts so interconnected that upon concurrent energization of both relays the normal closed circuit between a wire 198 which is connected to one side of the CR3 cam contacts and a plug hub 199 will remain open as it is normally. If, however, only one of the "b" transfer contacts is transferred, due to a dissimilarity in card holes, the circuit between wire 198 and plug hub 199 will be closed.

For comparison by three orders the three plug sockets 199 are interconnected by plug connec-

tions 200 and by means of plug connections 201 the closure of any of the three comparing circuits will complete a circuit from the line 160, through CR3 cam contacts, wire 198, R6b relay contacts now transferred, by way of example, R9b relay contacts now normal, plug hub 199, plug connection 201, plug hub 202, the pickup coil of the R4 relay and wire 203 to the line side 161. A hold circuit for R4 relay maintained through the *h* relay contacts and the CR4 cam contacts. Whenever the R4 relay is energized and held energized it will close its contacts R4b to thereby complete a circuit from the line side 160, wire 204, CR7 cam contacts, through R4b relay contacts, pickup coil of R5 relay to line side 161. The hold circuit for R5 is maintained by the *h* relay contacts, CR5 cam contacts to the line side 160.

From Fig. 9 it will be evident that CR5 cam contacts hold the R5 relay energized to the end of the cycle and during the first part of the next cycle, which is a total taking cycle, up to about 180°, during which time all of the impulses are transmitted by the emitter EM.

The R5 relay will close its 1-12 relay contacts, thereby rendering the EM character selecting impulse emitter effective for operation to select the characters according to the previously made plug connections.

The above is merely one of the many types of selecting means which may be provided for calling the character selecting device into operation at desired times.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A control device for printing alphabet type and digit type, said digit type being selected according to a numerical code, and said alphabet type according to an alphabetical code, alphabet type representing impulse exit sockets, digit type representing impulse exit sockets, impulse emitting means, a circuit network for causing said impulse emitting means to transmit impulses according to said numerical code to said digit type representing impulse exit sockets, and to transmit combinations of impulses according to said alphabetical code to said alphabet type representing impulse exit sockets, a printing mechanism of several orders, each comprising alphabet type and numeral type, a single control element for each order, means controlled by said element for selecting digit type in response to impulses according to said numerical code, means controlled by said element for selecting alphabet type in response to combinations of impulses according to the alphabetical code, and means comprising plug connections between the alphabet type representing impulse exit plug sockets and the digit type impulse exit sockets and the several orders of said elements to control the printing mechanism to print desired digit and alphabet type.

2. A control device for a printing mechanism having digit type and alphabet type which are selected according to a predetermined numerical and alphabetical code, respectively, impulse emitting means operable in a cycle of operation of said printing mechanism comprising means to

emit impulses which, according to a code select the digit type, and zone impulses which in combination with said impulses select the alphabet type according to a code, digit impulse exit plug sockets, alphabet representing impulse exit plug sockets, a circuit network from said impulse emitting means for transmitting said first named impulses to said digit impulse exit plug sockets to select digit type according to the numerical code, and for transmitting said first named impulses to said alphabet type representing impulse exit plug sockets according to the alphabet code, and selector means for connecting the zone impulse emitting means to said alphabet representing impulse exit plug sockets to direct zone impulses thereto to select alphabet type according to the alphabet code.

3. A control device for a printing mechanism having digit type and alphabet type, said digit type being selected by digit representing impulses, and the alphabet type by said digit impulses and zone impulses according to a predetermined alphabetic code, an impulse emitter operable in a cycle of operation of said printing mechanism comprising a rotatable element movable over digit segments in succession to emit digit impulses, and over zone segments to emit zone impulses, digit type representing impulse exit plug sockets, alphabet type representing impulse exit plug sockets, a circuit network consisting of wires extending from said digit segments for transmitting said digit impulses to correspondingly designated digit impulse exit plug sockets, and for transmitting said digit impulses to said alphabet type representing impulse exit sockets according to the alphabetical code, and selector means operable during the transmission of said zone impulses to connect according to the alphabet code the alphabet type representing exit sockets to the zone segments O, X, R to transmit said zone impulses to said alphabet type representing impulse exit sockets.

4. In a cyclically operable printing machine, a plural order printing mechanism having for each order alphabet type A-Z and digit type 1-9, a printing control magnet for each order, a plurality of alphabet type selecting means A-Z, one for each of the letters A-Z, a plurality of digit type selecting means 1-9, one for each of the digits 1-9, repeatedly operated source means of electrical impulses and operable for each cycle of the operation of the machine, means for connecting said source means to said alphabet type selecting means in such manner that to each of said alphabet type selecting means different combinations of electrical impulses are transmitted which will select alphabet type A-Z and for connecting said source means to said digit type selecting means in such manner that to each of said digit type selecting means digit representing electrical impulses are transmitted which will select digit type 1-9, and electrical connections made between the printing control magnets of the several orders of the printing mechanism and selected alphabet and digit type selecting means for causing electrical impulses to be transmitted from said selected alphabet and digit type selecting means to said printing control magnets to cause the latter to control said printing mechanism to print in each cycle of machine operation the desired digit and alphabet characters according to the electrical connections made.

5. In a cyclically operable printing machine, a plural order printing mechanism having for each order alphabet type A-Z selected by combinations

of electrical impulses and digit type 1-9 selected by single electrical impulses, a printing control magnet for each order, plug sockets each connected to an associated printing control magnet, a plurality of exit impulse plug sockets representing alphabet type A-Z, a plurality of exit impulse plug sockets representing digit type 1-9, repeatedly operated source means of electrical impulses and operable for each cycle of the operation of the machine, means for connecting said source means of electrical impulses to exit plug sockets A-Z in such manner that coded combinations of electrical impulses are repeatedly transmitted to said exit impulse plug sockets for selecting the alphabet type A-Z, and said source means to said exit plug sockets 1-9 in such manner that single electrical impulses are repeatedly transmitted to said exit impulse plug sockets for selecting the digit type 1-9, and means comprising variably made electrical plug connections between the plug sockets connected to the printing control magnets of the several orders of the

printing mechanism and said selected alphabet and digit type exit impulse plug sockets to cause impulses from selected alphabet and digit type exit impulse plug sockets to be transmitted to said print control magnets to select the desired alphabet and digit type for each cycle of machine operation.
